UNITED STATES PATENT OFFICE.

HARVEY L. FISHER AND JAMES W. BALLARD, OF TOLEDO, IOWA, ASSIGNEES
OF ONE-THIRD TO LEANDER CLARK, OF SAME PLACE.

RAILROAD-SCALES.

SPECIFICATION forming part of Letters Patent No. 398,824, dated March 5, 1889.

Application filed September 25, 1888. Serial No. 286,371. (No model.)

To all whom it may concern:

Be it known that we, HARVEY L. FISHER and JAMES W. BALLARD, citizens of the United States, residing at Toledo, in the county of 5 Tama and State of Iowa, have invented new and useful Improvements in Scales, of which the following is a specification.

Our invention relates to improvements in scales, and has especial reference to devices 10 for raising and lowering the track-rails of railroad-scales, so that they will be supported rigidly when not in use and can be quickly shifted onto their pivots when it is desired to weigh the cars.

15 Our invention consists in certain novel features, hereinafter described and claimed.

In the drawings, Figure 1 is a side view of a scale having our improved device applied thereto. Fig. 2 is a similar view looking at 20 the opposite side of a portion of the scales, showing the scales lowered into position for weighing. Fig. 3 is a transverse section on the line αx of Fig. 1. Fig. 4 is a detail view of one of the hinged supporting-levers, and 25 Fig. 5 is a detail view showing the adjustable upper bearing for said lever.

Referring to the drawings particularly by letter, A A designate the parallel longitudinal base-beams of the frame of the scales.

30 B designates the platform, and C the hangers for the same, all of the usual construction. At various points along the frame we secure the cross-bars D, and on these cross-bars we secure the bearings E, in which are journaled 35 the rock-shafts F, having on their outer ends the crank-arms G extending in opposite directions from said shaft. The ends of these crank-arms are connected by the longitudinal links or connecting-rods H, as shown. At

40 about the center of the scale we mount the transverse rock-shaft I, having rigidly secured to its outer end the three-armed lever J. Two of the arms of this lever extend from the shaft in a diametrically-opposite direction, 45 while the third arm, K, extends from the shaft at an angle to the said two arms. The ends of the aligned arms are connected by the links L with the ends of the adjacent crank-arms G, and the links L, extending between the two 50 arms of the lever J, and the adjacent crank-

arms on one side are crossed, as shown, so that the said crank-arms at both ends of the scales will be simultaneously operated to rotate the rock-shafts F in the proper direction to throw the upper portions of the hinged levers out of 55 engagement with the upper bearing. The end of the arm K has the lower end of a link, M, pivoted thereto, the upper end of said link being pivoted to the shorter arm of the bent operating-lever N, which is fulcrumed on the 60 track-rails of the scale, and is adapted to engage a hook, O, secured thereto, so as to lock the scale firmly in its raised position.

P designate a series of hinged levers, which have their lower members, S, secured 65 rigidly on the rock-shafts F and projected upward therefrom. The upper members, Q, of the levers P have their lower ends hinged to the lower members, S, and their upper ends resting in bearings R, secured to the under 70 side of the track-rail of the platform of the scale. The lower member, S, of the lever P is provided at its upper end with a transverse groove, T, which is nearly circular in cross-section, and projecting from one side of the member S is an oblique arm, U, as shown. The upper member, Q, of the lever is provided at its opposite ends with the cylindrical journals V V. The lower journal V engages the groove T of the lower member of the hinge, and the upper journal engages the bearing R, as shown. From one side of the member Q projects a pin, W, which extends through a perforation in the upper end of the arm U, and is provided at its extremity with a nut, X. The pin 75 W is hinged to the member Q of the lever, so as to allow the proper movement of the members upon each other. This construction, however, is not essential, as the said pins may be secured rigidly to the upper member or 80 formed integral therewith, and curved outward and downward therefrom on the arc of the circle of which the lower bearing V is the center. A spring, i, is coiled around the pin W, between the nut X and the arm U, for 85 a purpose presently set forth.

The bearing R comprises a base-plate, Y, the bearing-plate Z, and a wedge, a. The base-plate Y is secured to the under side of the track-rail of the platform, and is provided 90

at one end with the depending lug *b*. A bearing-plate, *Z*, is secured beneath the base-plate *Y* by means of the bolts *c c*, extended vertically through the base-plate and the bearing-plate, as clearly shown. The bearing-plate is provided on its upper side with an inclined groove, *d*, in which the wedge *a* rests, and the said wedge *a* is provided at its smaller end with a threaded cylindrical extension, *e*, which 5 projects through the lug *b*, and is provided with a securing-nut, *f*, turning up against said lug. By this means the wedge can be readily drawn inward or loosened to be pushed outward, so that the bearing-plate will be secured at the proper height for the successful 10 operation of the hinged levers. On its under side the bearing-plate *Z* is provided with the depending ribs or flanges *g h*, having a concave surface between them. The flange *h* is 15 somewhat longer or deeper than the flange *g*, and is arranged at the proper side of the bearing-plate to limit the movement of the upper end of the hinged levers *P*. The upper bearing *V* of the hinged lever rests in the concave 20 recess between the flanges *g h*.

In practice the normal position of the parts is that shown in Fig. 1, with the members of the hinged levers aligned and having their upper ends engaging the bearings *R*. In this 25 position the platform of the scale will be held off the hangers *C C*, so that the train can run over the scale without operating the same, and thereby causing wear of the parts. When it is desired to weigh a car, the lever *N* is disengaged from the hook *O* and thrown upward, as shown in Fig. 2, and the motion of 30 the lever is communicated through the several links and the three-armed lever *J* to the rock-shafts *F*, thereby rotating the said shafts 35 and operating the hinged levers.

As the shafts *F* are rotated, the lower members, *S*, of the hinged levers will be thrown over toward the beams *A*, as shown in Fig. 2, of the frame of the scale, thereby lowering 40 the lower bearing *V* of the upper member of the lever. At the same time the arm *U* will compress the springs *i* on the pins *W* between said arm and the nut *X*, so that the 45 said springs will exert a tension against said nut to prevent the upper member of the lever being carried outward by the motion of the lower member. The said upper member of the lever is thus caused to move outward at its lower end and downward at its upper 50 end. When the upper end of the member *Q* has been lowered sufficiently to clear the flange *g*, the tension of the spring will be overcome, and the said lever will then be thrown outward into the position shown in 55 Fig. 2, so that the track-rails of the scale-platform will be supported by the hanger *C*, so that the car may be weighed, as will be readily understood.

It will thus be seen that we have provided a very simple mechanism by which the scale-platform may be rigidly supported when not in use, and can be instantly released for weighing purposes when so desired. The several parts of the device are simple in their construction, and there are no complicated 65 combinations or arrangements, so that it can be manufactured at a small cost.

Having thus described our invention, what we claim, and desire to secure by Letters Patent, is—

1. In an attachment for platform-scales, the combination of the series of transverse rock-shafts *F*, the crank-arms on the outer ends of the said shafts, the links connecting said crank-arms, the rock-shaft *I*, the three-armed lever on said shaft, links connecting said lever with the crank-arms, the hinged levers on the rock-shafts *F*, adapted to support the platform of the scale, the operating-lever mounted on the platform, and the link 80 connecting the same with the three-armed lever, as set forth.

2. The combination of the platform, the bearings *R*, secured to the under side thereof, the transverse rock-shafts arranged below the platform, the hinged levers comprising the lower members secured rigidly on the rock-shafts, and the upper members supported by the lower members and adapted to engage the bearings *R* when the two members are 95 in alignment and be disengaged therefrom when the members are at an angle to each other, and mechanism for rotating the rock-shafts, as set forth.

3. In an attachment for platform-scales, the hinged lever comprising the lower member, *S*, having the transverse groove *T* in its upper end and provided with the arm *U*, and the upper member having its lower end journaled in the groove *T*, a pin projecting from 100 said upper member through the arm *U*, and a spring coiled around said pin beyond the arm *U* and secured on said pin, as set forth.

4. The combination, with the platform, of the base-plate *Y*, secured thereto, the bearing-plate *Z*, secured to said base-plate and having the flanges *g h*, and the concave recess between said flanges, the wedge adjustably secured between the base-plate and the bearing-plate, the hinged levers engaging the 115 concave recess in the bearing-plate, and mechanism for operating said levers, as specified.

In testimony that we claim the foregoing as our own we have hereto affixed our signatures 120 in presence of two witnesses.

HARVEY L. FISHER.
JAMES W. BALLARD.
